UNITED STATES PATENT OFFICE.

CHARLES FREBORG, OF KANKAKEE, ILLINOIS, ASSIGNOR TO PRICE AND TEEPLE PIANO COMPANY, OF CHICAGO, ILLINOIS, A CORPORATION OF ILLINOIS.

PNEUMATIC PLAYER.

1,233,336.

Specification of Letters Patent. Patented July 17, 1917.

Application filed November 18, 1913. Serial No. 801,607.

To all whom it may concern:

Be it known that I, CHARLES FREBORG, a citizen of the United States, residing at Kankakee, in the county of Kankakee and 5 State of Illinois, have invented certain new and useful Improvements in Pneumatic Players, of which the following is a specification.

The principal object of my invention is 10 to provide a new and improved pneumatic player suitable for pianos. Another object of my invention is to provide an improved construction for the bleed-holes of a pneumatic player. Another object of my invention 15 is to provide a bleed-hole construction that shall be simple and inexpensive to make, not liable to get out of order and rugged and serviceable in use. Another object of my invention relates to a guide for the button on the diaphragm that actuates the valve for each pneumatic of the player. All these 20 objects and others will be made apparent in the following specification and claims, taken with the accompanying drawings, in which—

25 Figure 1 is a transverse section on the line 1, 1 of Fig. 4.

Fig. 2 is a section on the line 2, 2 of Fig. 4.

30 Fig. 3 is an elevation looking in the direction of the arrow 3 of Fig. 4, certain parts being broken away to show details of construction more clearly.

35 Fig. 4 is a plan view with certain parts broken away to exhibit the interior structure.

In these drawings I have illustrated one 40 specific embodiment of my invention to enable me to explain its principle and mode of operation. It will be understood that the invention is defined in the appended claims. The apparatus shown in the drawings comprises part of the mechanism of a piano player. The vacuum chamber 6 extends substantially across the entire length of the 45 piano. Along its floor there are conical depressions 7 entirely covered by loose leather diaphragms 8. Each cup 7 is connected by a conduit 9 to a rubber tube 10 which goes to a respective hole of the tracker board. 50 Above the vacuum chamber 6 is a series of valve chambers 11, each valve chamber 11 registering with a corresponding cup 7, and each valve chamber 11 being connected by

a rubber tube 12 to a respective pneumatic. Within each valve chamber 11 is a pair of 55 valves 13 and 14 fixed on the same stem 15. This stem 15 is mounted in guides 16 and 17 and the lower end of the stem 15 rests on a button 18 fixed to the center of the diaphragm 8. The button 18 may be of felt 60 and may be secured to disk, 40, of fiber which in turn is directly secured to the diaphragm 8. Depending from the button 18 is a slender stem 19 which enters the short 65 guide tube 20. This guide tube 20 is fitted tightly in the bottom wall of the vacuum chamber 6 and projects up into the conduit 9. A cap 21 is glued over the lower end of the tube 20 to keep the vacuum chamber air-tight. 70

Extending along the length of the vacuum chamber 6 there is a square brass tube 22 with its upper wall a little thicker than the other walls. This tube 22 is connected at one end by a conduit 23 to the vacuum chamber 75 6. It is secured in place by a series of screws 24 which enter the rear member 25.

From the series of conduits 9 there are 80 respective vertical branches 26 that go up and end along the under surface of the tube 22. Small holes 28 tapered to form valve seats are drilled in the lower wall of the tube 22 in register with the respective branch conduits 26 and needle valves 27 have screw threaded engagement through the upper 85 wall of the tube 22 and seat on the respective valve seats 28. The upper wall of the tube 22 being thicker, makes it possible to get sufficient screw threaded engagement for the stems of the valves 27. The fit of these 90 screw threads is made tight so that they will stay in adjustment.

When the device is operating in a normal manner a partial vacuum is maintained in the vacuum chamber 6 and this same degree 95 of vacuum is communicated through the branch passage 23 along the interior of the tube 22 and through the bleed-holes 28 and branches 26 of the conduits 9. Hence the diaphragms 8 have the same vacuum on their 100 upper and under sides and therefore the parts, by their gravity and by the unbalanced force on valves 14, take the positions shown in Fig. 1. When a hole of the tracker board is uncovered this permits atmospheric 105 air to enter a tube 10 and raise the dia-

phragm 8; some of this air also enters the tube 22 through the bleed-hole 28, but not enough to unduly reduce the pressure in the conduit 9. The raising of the diaphragm 8 5 raises the valve stem 15 and causes the valve 13 to close the valve chamber to the external air and opens the valve chamber 11 to communication with the vacuum chamber 6. Therefore the air in the respective pneumatic 10 rushes therefrom through the tube 12 under the valve 14 into the vacuum chamber 6. Accordingly the pneumatic collapses, which actuates the piano action.

The button 18 on the diaphragm 8 is constrained to move in a vertical path without angular change of position by reason of the stem 19 engaging the guide tube 20. Thus even if it should happen that the valve stem 15 rested a trifle at one side of the center of 20 the button 18, the valve stem 15 will be definitely actuated nevertheless. If the guide members 19 and 20 were absent and if the valve stem 15 happened to rest on the button 18 a little at one side of its center, the button 25 18 might tend to tilt and rise at one side only and thus fail to actuate the valve stem 15. The mechanism that I have just described obviates this difficulty.

Just before the hole in the tracker board 30 which connects with the tube 10 is closed the air in the conduit 9 is at atmospheric pressure. Immediately after such closure the continued flow of air from the conduit 9 through the branch passage 26 and bleed-hole 28 reduces the pressure in the conduit 9 making it a partial vacuum. This reduction of pressure in the conduit 9 is communicated in like degree to the cup 7 and the reduction of pressure under the diaphragm 8 35 causes the diaphragm 8 to fall, and drops the stem 15 so that the valve 13 opens the valve chamber 11 to the outside air and the valve 14 closes the valve chamber 11 to the vacuum chamber 6. Thereupon the atmospheric air rushes in above the valve 13 and through the tube 12 to the pneumatic, inflating the latter and restoring it to its normal condition. The bleed-hole opening 28 should be adjusted in size with considerable 40 precision. If it is opened too much, then the uncovering of the opening in the tracker board will not reduce the vacuum in the conduit 9 quickly enough to promptly actuate the diaphragm 8. On the other hand if the 45 bleed-hole 28 is not opened enough, then when the tracker board opening is closed the restoration of the vacuum in conduit 9 will not occur quickly enough and the piano will not "repeat" properly.

One advantage of the bleed-hole construction that I have disclosed herein is that the branch 26 extends vertically up to the bleed-hole 28. Accordingly if any particles of dust or other foreign matter enter the tube 50 10 and the conduit 9 they will remain in the

conduit 9 rather than drift up the branch 26 and obstruct the bleed-hole 28; whereas if the conduit 26 extended horizontally instead of vertically, the particles might lodge in it and obstruct the bleed-hole.

Where bleed-holes are provided with adjustable valves and individual valve seat structures are made, the labor and expense involved are considerably greater than with my arrangement. I take the single tube 22 70 of brass or other material and drill the holes in the upper thick wall with a gang drill. I use drills with narrow points and run them just far enough to cut the valve seats 28. Next I tap the holes in the upper 80 extra thick wall with screw threads and then apply the screw valves 27. Finally the whole tube is fastened in place with the screws 24. It will be seen that far less labor is involved than if individual valve seat 85 structures were made and applied.

I claim:

1. In a pneumatic player, a vacuum chamber, a series of conduits communicating therewith from the respective openings of the tracker board, branches from the respective conduits, and a tube separate from the tracker board and connected to the ends of said branches by respective bleed-holes, said tube being located adjacent to and connected 90 to said vacuum chamber.

2. In a pneumatic player, a vacuum chamber, a series of conduits communicating therewith from the respective openings of the tracker board, parallel branches from the respective conduits adjacent said vacuum chamber, and a tube lying across the ends of said branch conduits with respective bleed-holes through the wall of said tube connecting the interior thereof with the respective branch conduits, said tube being directly connected adjacent its ends to said vacuum chamber.

3. In a pneumatic player, a vacuum chamber, a series of conduits communicating therewith from the respective openings of the tracker board, branches extending vertically up from the respective conduits, a separate metal tube lying over the upper ends of said branches, said tube having 110 bleed-holes in its wall connecting the interior thereof with the respective branch conduits, and said tube being connected to said vacuum chamber.

4. In a pneumatic player, a vacuum chamber, a series of conduits communicating therewith from the respective openings of the tracker board, branches from the respective conduits, a separate metal tube independent of the tracker board lying across 120 the ends of said branch conduits with respective bleed-holes through its side wall connecting with the ends of said conduits, and screw valves passing through the wall of the tube opposite said bleed-holes, said 130

valves being adapted to engage said bleed-holes as valve seats.

5. In a pneumatic player, a vacuum chamber, a series of conduits communicating therewith from the respective openings of the tracker board, branches from the respective conduits, an integrally formed tube overlying the ends of said branches, said tube having transverse holes through its 10 side walls alining in pairs, the holes on one side connecting with the said branch conduits and being tapered from valve seats and the holes on the opposite side being larger and screw threaded, and screw valves 15 engaging said screw threaded holes and adapted to coact with the valve seats.

6. In a pneumatic player, a vacuum chamber, a series of conduits communicating therewith from the respective openings of 20 the tracker board, said conduits extending for a certain distance across the bottom wall of the vacuum chamber, branch conduits therefrom extending vertically up through the rear wall of the chamber, and a long 25 tube overlying the upper ends of said branch conduits, said tube having holes through its under side wall connecting with the branch conduits, and valves mounted in the tube to control said openings.

30 7. In a pneumatic player, a vacuum chamber, a series of conduits communicating therewith from the respective openings of the tracker board, said conduits extending for a certain distance across the bottom wall 35 of the vacuum chamber, branch conduits therefrom extending vertically up through

the rear wall of the chamber, a long tube of square cross section overlying the upper ends of said conduits, the under side wall of said tube having holes connecting with 40 said branch conduits, the upper wall of the tube being relatively thick, and screw valves extending transversely down through said upper thick wall having screw threaded engagement therewith, said valves being 45 adapted to control the openings in the lower side of the tube.

8. In a pneumatic player, a vacuum chamber, a series of conduits communicating therewith from the respective openings of 50 the tracker board, branches from the respective conduits, and a tube connected to the ends of said branches by respective bleed-holes, said tube being in permanent communication with said vacuum chamber. 55

9. In a pneumatic player, a vacuum chamber, a series of conduits communicating therewith from respective openings of the tracker board, vertically extending branches from the respective conduits, a tube overlying 60 the upper ends of said branches with respective bleed-holes through the wall of said tube connecting the interior thereof with the respective branch conduits, and a short conduit directly connecting said tube 65 with said vacuum chamber.

In testimony whereof, I have subscribed my name.

CHARLES FREBORG.
